UNITED STATES PATENT OFFICE.

WILLIAM BICKERTON CROMPTON, OF WALKDEN, ENGLAND.

MACHINE FOR BOBBIN-TO-BOBBIN SIZING.

Application filed December 16, 1927, Serial No. 240,593, and in Great Britain December 30, 1926.

This invention relates to improvements in machines for sizing or other treatment of artificial silk and analogous yarns of the type in which the yarn is drawn off a set 5 of bobbins or cheeses arranged horizontally in a winding frame or reel.

According to the invention the winding bobbins or cheeses are driven by frictional contact with the periphery of a number of 10 wheels or discs, each bobbin contacting with or resting upon a wheel or disc at one or both ends of the bobbin and each wheel or disc being engaged with two adjacent bobbins.

25 The invention will be described with reference to the accompanying drawings.

Fig. 1 is a side elevation of the machine.

Fig. 1^a is a continuation of Fig. 1.

Fig. 2 is a plan of same.

20 Fig. 2^a is a continuation of Fig. 2.

Fig. 3 is an elevation from the front end of the machine.

Fig. 4 is an elevation from the reel end of the machine.

25 Fig. 5 is an enlarged detail view of the bobbin drive.

Fig. 6 is a plan of same also showing construction of the bobbins.

Fig. 7 is a sectional view of same also 30 showing drive for the thread guides.

Fig. 8 is a detail of the bearings for the bobbins.

Fig. 9 is a detail view showing a modified drive of the bobbins.

35 Fig. 9^a is a detailed view partly in section of bobbin bearing.

The machine comprises a creel A in which the bobbins α carrying the unsized yarn are mounted, a sizing trough B, a heating plate

40 or cell C and a frame D in which are mounted the bobbins or cheeses d on to which the sized yarn is wound.

The sizing trough B is mounted on a bracket E which can be moved up and down

45 on the pillars E^1 by the chain e and ratchet wheel e^1 . Mounted on the pillars E^1 are

fixed brackets E^2 which support the roller B^1 rotating in the trough B and a comb B^2 through the dents of which the unsized yarn

50 passes before coming into contact with the roller B^1 .

The heating cell C is heated by steam or in any other suitable way and carries between it and the trough B a comb C^1 which is given a transverse reciprocating motion 55 by the cam c on the end of the shaft of the roller B^1 to impart a rolling action to the yarn. The roller B^1 is rotated by the pulley b on the end of the roller shaft, the pulley b being driven by the rope or belt b^1 . 60 A second comb C^2 is carried at the front end of the cell C, this comb being either stationary or reciprocated as desired.

The frame D on which the bobbins d are mounted is preferably arranged at an angle 65 as shown in Fig. 1^a so that the yarn passing to the bobbins d will be spread out at a greater angle.

The bobbins d are arranged in rows across the frame each pair of rows being driven 70 from friction discs f mounted on a shaft F extending across the machine so that there is one shaft F for each two rows of bobbins the shaft extending between and below the bobbins. Two friction discs drive each 75 bobbin and engage with discs or wheels g^1 and g^2 one at each end of the spindle G on which the bobbin is mounted. The disc g^1 is formed integrally with the spindle G and the disc g^2 is formed with a central 80 bush g^3 which screws on to the threaded end of the spindle G (see Fig. 6) so that the bobbin d is clamped between the discs g^1 and g^2 and will rotate therewith. The ends of the spindle G project beyond the discs g^1 and g^2 and are carried in bearings h mounted 85 in a bar H extending from front to back of the frame. There may be any number of bars H according to the number of bobbins d there are across the frame. 90

The bearings h (see Fig. 8) are preferably formed of compressed fibrous material to reduce the wear on the spindle and are each formed with two transverse slots h^1 and h^2 the slot h^1 being deeper than the slot h^2 . 95 The deeper slot h^1 receives the end of the spindle G when in the operative position i. e. when the discs g^1 and g^2 are in engagement with the driving discs f and the shallow slot h^2 is for the purpose of receiving 100 the ends of the spindle G when the bobbin d is lifted out of the operative position. The

relative position of the slots h^1 and h^2 are preferably the same throughout the frame. Each bearing h serves for the ends of the spindle G of two adjacent bobbins d and it is therefore preferably divided by the plate h^3 to position the bobbins transversely.

Instead of being driven by friction discs the bobbins may be driven by rollers f^3 contacting directly with the flanges d of the bobbins. Each roller f^3 extends across the frame driving all the bobbins in one row (see Fig. 9). The spindles of the bobbins are carried in eyelets h^5 , preferably made of porcelain, and provided with a slot h^4 to allow of their insertion thereinto.

A thread guide K is provided for each bobbin d to direct the yarn thereto. The thread guides K are mounted in rows on transverse rods K^1 above the bobbins d each being capable of adjustment on its rod by the set screw k^3 . The thread guide rods K^1 are mounted at each end on longitudinal rods K^2 carried on pivoted levers K^3 so that by imparting a rocking motion to the levers K^2 the rods K^1 and with them the thread guides K are given a reciprocating movement over the bobbins d .

The shafts F are driven from the change speed gear box L controlled by the handle L^1 through the shaft M on which are mounted worms M^1 which gear with worm wheels f^1 on the shafts F . The foremost shaft F is provided with a worm f^2 which gears with a worm wheel on a short shaft m on which is mounted a gear wheel m^1 gearing with a wheel M^2 mounted on the shaft M^4 which carries a cam m^2 . The cam m^2 engages with runners n on a cross shaped lever N pivoted at n^1 so that as the cam m^2 rotates an oscillating movement about the pivot n^1 is given to the lever N . The upper end of the lever N is slotted at n^2 and the end o of a connecting rod O is fixed in the slot n^2 . The other end of the connecting rod O is connected to an arm K^4 connected to one of the pivoted levers K^3 so that as the lever N oscillates about the pivot n^1 a corresponding oscillating movement is imparted to the lever K^3 and the rods K^1 and thread guides K are reciprocated over the bobbins d .

The sizing roller B^1 and the comb C^1 are driven through the rope or belt b^1 from a pulley f^2 on the end of one of the shafts F .

The yarn passes from the bobbins a through the teeth of the comb B^2 over the sizing rollers B^1 through the teeth of the reciprocating comb C^1 to the heated cell or plate C . The yarn comes into contact with a greater or less surface of the plate C according to the height of the roller B^1 which is adjustable, the surface of the plate with which they are allowed to come into contact depending upon the nature of and thickness of the yarn, the speed of travel being varied by the gear box L .

After leaving the heated plate C and passing through the comb C^2 the yarn is guided by the thread guides K to the bobbins d in the winding frame D .

What I claim as my invention and desire to protect by Letters Patent is:—

1. A yarn sizing machine of the type referred to comprising a series of bobbins from which the yarn is drawn off, a roller over which the yarn is passed to supply size thereto, a drying chest along which the yarn travels, a second series of bobbins on to which the yarn is wound, a frame carrying said series of bobbins, flanges on the ends of said bobbins, a plurality of rows of shafts extending across the frame between each row of bobbins, discs mounted on the shafts and contacting with the flanges of a pair of bobbins in adjacent rows so that each disc drives the bobbins by frictional contact therewith and means for driving the transverse shafts.

2. A yarn sizing machine of the type referred to comprising a series of bobbins from which the yarn is drawn off, a roller over which the yarn is passed to supply size thereto, a drying chest along which the yarn travels, a second series of bobbins on to which the yarn is wound, a frame carrying said series of bobbins, flanges on the ends of said bobbins, a plurality of rows of shafts extending across the frame between each row of bobbins, worm wheels carried by said shafts, discs mounted on the shafts and contacting with the flanges of a pair of bobbins in adjacent rows so that each disc drives two bobbins by frictional contact therewith, a plurality of longitudinal bars carried by the frame and bearings for the bobbin spindles carried by the longitudinal bars, a shaft running longitudinally of the frame and worms mounted on said shaft to gear with the worm wheels on said transverse shaft.

3. A sizing machine for artificial silk and analogous yarns of the type in which the yarn is drawn off one set of bobbins or cheeses and wound on to another set of bobbins or cheeses comprising the combination with a creel of bobbins mounted therein, a sizing trough adjustable as to height, means for raising and lowering the trough, a sizing roller mounted therein, a heated drying plate, a reciprocating comb at one end of the plate, a stationary comb at the other end of the plate, a winding frame, bobbins mounted therein, friction discs attached to said bobbins, a plurality of rows of shafts extending across the frame between each row of bobbins, worm wheels carried by said shafts, friction discs mounted on said shafts and contacting with said friction discs on said bobbins, a plurality of longitudinal bars carried by the frame and means for driving said shafts, bearings for the spindles of the

bobbins having slots therein of different depths to receive the spindles when the bobbins are in the operative and non-operative position respectively, thread guides for guiding the yarns to the bobbins, reciprocating transverse rods to impart a rolling motion to the yarn on which the thread guides are

mounted and means for giving a reciprocating motion to the transverse rods substantially as described.

In testimony whereof I have hereunto set my hand.

WILLIAM BICKERTON CROMPTON.
